UNITED STATES PATENT OFFICE.

EDWARD CARLSON, OF BUFFALO, NEW YORK, ASSIGNOR TO JAMES H. RAND, JR., OF TONAWANDA, NEW YORK.

RECORD DEVICE.

Application filed July 3, 1924. Serial No. 724,061.

This invention relates to record or index devices and more particularly to card index or record cabinets and trays or slides therefor.

In certain index or record cabinets heretofore in use, there have been provided a plurality of movable slides or trays adapted to support a plurality of cards or other record devices substantially flatwise in predetermined overlapping relation. The trays or slides of these devices have been comparatively shallow having substantially parallel upright sides and a front end or wall secured to the body of the tray, which, when the tray is in closed position in the cabinet, closes the opening between adjacent portions of the cabinet. Certain of these trays have also been provided with front aprons or plates adapted to overlie a portion of the body of the tray and to provide an inclined support or rest for a number of the cards to maintain the edges of the cards in the series in substantial horizontal alinement. These devices also usually include a movable follower or stop member positioned in the tray, and which has a portion adapted to engage an end of the series of record devices in the tray to hold said devices in the tray and prevent their movement in one direction longitudinally of the tray.

Heretofore, in certain of these devices, the trays or slides have been provided with hinged tail pieces having hooks or projections thereon adapted to engage with hooks or projections on parts of the cabinet whereby, when the trays are partially withdrawn from the cabinet the trays will be suspended in substantially vertical positions in front of the cabinet by the engagement of the hooks on the tray with the hooks of the cabinet.

The objects of the present invention are to provide card index or record trays having movable end walls; also to provide card index or record trays having combined movable end walls and followers or stops; and also to provide improvements in card-record devices in the other respects hereinafter set forth and claimed.

50 In the accompanying drawings—

Fig. 1 is a perspective view of the front members of a record or index tray or slide constructed in accordance with this invention.

55 Fig. 2 is a fragmentary longitudinal sec-

tion thereof, showing the movable end wall of the slide moved away from the body portion and the follower disengaged from the record devices supported by the slide.

Figs. 3 and 4 are transverse sectional elevations on lines 3—3 and 4—4 respectively, Figs. 6 and 5.

Fig. 5 is a longitudinal sectional elevation of the front end of the slide on line 5—5, Fig. 10, but on an enlarged scale.

Figs. 6 and 7 are similar views thereof on lines 6—6 and 7—7, Fig. 12.

Fig. 8 is a transverse section on line 8—8, Fig. 12 showing the connecting means between the movable front wall member and the slide body, moved to position to permit disengagement of these parts.

Fig. 9 is a longitudinal section showing the parts in another position.

Fig. 10 is a plan view of the complete tray or slide.

Fig. 11 is a plan view of the front portion of the slide showing the record devices turned back to disclose the engagement of the follower therewith.

Fig. 12 is a plan view of the front end of the tray with the follower removed.

Fig. 13 is a similar view with the movable front wall member moved away from the body portion of the slide.

Fig. 14 is a sectional plan view of one corner thereof on line 14—14, Fig. 7.

Referring to the drawings, 15 designates a cabinet in which are positioned a plurality of slides or trays 16. These slides or trays are movable into and out of the cabinet and are adapted to contain a plurality of cards, record members or devices.

In Fig. 10 there is shown one of these trays 16 carrying a plurality of index cards 17 arranged in predetermined overlapping relation substantially flatwise in the tray. The tray generally comprises a bottom 18 provided with the sides 19 formed to provide lengthwise extending guide members or portions 20 which are adapted to engage tongues or projections 21 on the cards to maintain the cards connected with the tray. The tray is preferably provided with a rear stop portion 22 against which an end card of the series is adapted to abut so as to limit longitudinal movement of the cards in the tray in one direction.

23 designates the movable end wall of the tray. This end wall is preferably mounted

so that it may be moved to and from a position in substantial contact with the body portion of the tray and has connected to it a follower or stop member 24 which has a portion for engaging an end of the series of record devices in the tray for compressing the series of record devices and maintaining them against movement lengthwise of the tray in the other direction. In the particular construction shown the tray is formed of sheet metal, and the movable end wall is made of a portion of the upright wall 25, and a portion forming an angularly extending projection or tongue 26 which overlies a portion of the bottom of the tray. This portion 26 is provided with one or more guide slots 27 into which tongues or guide members 28 on the tray bottom project. The movable end portion and the tray proper are provided with interengaging parts whereby the movable end wall may be releasably secured in its closing position substantially in contact with the body portion of the tray. For this purpose, in the embodiment of the invention shown, the bottom of the tray is provided with an aperture 29 and the part 26 of the front wall member is provided with a lug or projection 30 carried by a spring 31 which is adapted to engage the apertured portion of the tray bottom when the upright end wall member is in substantial contact with the body of the tray, so as to releasably secure it in such position. To permit the upright end wall to be moved outwardly from the body of the tray, the finger of the operator is pressed against the lug, forcing it up out of the apertured portion of the body of the tray, whereupon the upright end wall may be drawn forwardly out of contact with the body of the tray.

The movable end portion of the tray is provided with guide means, in addition to the lugs 28 and slots 27, before mentioned, for guiding the tray end and maintaining it in correct alignment in its movements. For this purpose the side edges of the part 26 are formed with vertical, parallel side flanges 31^a which are received in recesses 31^b in the sides 19 of the tray proper, see Figs. 2, 3 and 13.

The follower or movable stop member is preferably releasably connected to the movable end wall member. In the embodiment shown, this is accomplished by forming the upright end wall with a bent-over flange 32, thereby providing substantially a channel 33. The follower is provided with one or more flanges 34 which are adapted to engage in the channel of the front wall member to connect these parts together. The follower is preferably provided adjacent its card or record-engaging portion with a pair of side tongues or projections 35. These projections are adapted to engage beneath

the flanges of the sides of the tray in order to guide the follower in its sliding movements on the tray.

With the movable end wall and follower of this invention, the follower may be readily actuated to engage or release the cards from the outside of the cabinet by moving the end wall. At the same time, this construction does away with the necessity of a separate follower block and means for retaining said follower block in fixed position when in engagement with the cards, and also the necessity of a front apron, or the like, to protect the cards from the operating parts of the follower.

I claim as my invention:—

1. In a record-holding tray, the combination of a tray body and a part providing a stop for engaging a portion of a series of record devices therein to prevent movement of said series in one direction longitudinally of said tray, a movable follower member at the front end of said tray and having a part adapted to engage a portion of said series for releasably preventing movement of said series longitudinally of said tray in the other direction, a front wall member movably mounted on said tray for movement toward and from the body portion of said tray and a connection between said front wall member and said follower whereby said follower may be moved by said front wall member in its movements to and from said body portion to cause said follower part to engage or disengage said series of record devices.

2. In a record-holding tray, the combination of a tray body and a part providing a stop for engaging a portion of a series of record devices therein to prevent movement of said series in one direction longitudinally of said tray, a movable follower member at the front end of said tray and having a part adapted to engage a portion of said series for releasably preventing movement of said series longitudinally of said tray in the other direction, and a front wall member slidably mounted on said tray for movement toward and from the body portion of said tray.

3. In a record-holding tray, the combination of a tray body and a part providing a stop for engaging a portion of a series of record devices therein to prevent movement of said series in one direction longitudinally of said tray, a movable follower member at the front end of said tray and having a part adapted to engage a portion of said series for releasably preventing movement of said series longitudinally of said tray in the other direction, a front wall member slidably mounted on said tray for movement toward and from the body portion of said tray, and interlocking means on said front wall and said body for releasably maintain-

- ing said front wall in position close to said body.
4. In a record-holding tray, the combination of a tray body and a part providing a stop for engaging a portion of a series of record devices therein to prevent movement of said series in one direction longitudinally of said tray, a movable follower member at the front end of said tray and having a part adapted to engage a portion of said series for releasably preventing movement of said series longitudinally of said tray in the other direction, a front wall member movably mounted on said tray and a connection between said front wall member and said follower whereby said follower may be moved by said front wall member in its movements to and from said body portion to cause said follower part to engage or disengage said series of record devices, and interlocking means on said front wall and said body for releasably maintaining said front wall in position close to said body.
5. In a record device, a plurality of record devices adapted to be releasably maintained in spaced recumbent position, a tray having a part for supporting said devices in recumbent positions and side parts for engaging portions of said record devices to maintain them connected to said tray, and a tray front member movably mounted on said tray and having a part adapted to engage one of said record devices to maintain said record devices in proper spaced position on said tray.
6. A record tray having a bottom and a pair of opposite sides for maintaining a series of record devices in recumbent positions thereon, and a movable tray front member forming a releasable closure for the front of said tray and having a rigid wall adapted to engage one end of said series of record devices for maintaining said devices in recumbent position in said tray.
7. A record tray having parts for supporting a plurality of record devices in recumbent positions thereon and a combined follower and tray front member movably mounted on said tray, said follower having a part adapted to engage one of said record devices to maintain said record devices against movement lengthwise of said tray, said follower and tray front being movable relatively to said tray to and from positions in which said follower part engages said record device.
8. In a record-holding tray, the combination of a part providing a stop for engaging a portion of a series of record devices disposed in predetermined order flatwise on said tray to prevent movement of said series in one direction longitudinally of said tray, a combined front wall member and follower having a part adapted to engage a portion of said series and movable relatively to said tray toward and from said series for releasably preventing movement of said series longitudinally of said tray in the other direction.
9. In a record tray, the combination of a body portion, opposite side walls and parts adapted to retain a series of record devices in predetermined order flatwise thereon, an end wall movably connected to said body portion whereby it may be moved into or out of contact with said body portion, interlocking parts on said end wall member and said body portion for releasably retaining said end wall in contact with said body portion.
10. In a record tray, the combination of a body portion, opposite side walls and parts adapted to retain a series of record devices in predetermined order flatwise thereon, an end wall movably connected to said body portion whereby it may be moved into or out of contact with said body portion, interlocking parts on said end wall member and said body portion for releasably retaining said end wall in contact with said body portion.
11. In a record tray, the combination of a body portion, opposite side walls and parts adapted to support a series of record devices in predetermined order flatwise thereon, an end wall movably connected to said body portion whereby it may be moved into or out of contact with said body portion, interlocking parts on said end wall member and said body portion for releasably retaining said end wall in contact with said body portion, and a follower member disposed flatwise in said tray and connected to said movable end wall to be moved therewith into and out of contact with a portion of said series of record devices.
12. In a record tray, the combination of a body portion having parts adapted to support a series of record devices in predetermined order, an upright end wall having a portion extending at an angle thereto and contacting with a portion of said body, cooperating guide parts on said end wall extension and said body for permitting said upright end wall to be moved toward or from said body portion, and interlocking parts on said body portion and said wall extension for releasably securing said upright end wall substantially in contact with said body portion.

EDWARD CARLSON.
